UNITED STATES PATENT OFFICE.

WILFRED I. OHMER, JOSEPH N. KELLY, AND WALLACE M. KELCH, OF DAYTON, OHIO; SAID KELLY AND KELCH ASSIGNORS TO SAID OHMER.

LETTER-CANCELING MACHINE.

SPECIFICATION forming part of Letters Patent No. 663,663, dated December 11, 1900.

Application filed April 4, 1899. Serial No. 711,752. (No model.)

To all whom it may concern:

Be it known that we, WILFRED I. OHMER, JOSEPH N. KELLY, and WALLACE M. KELCH, citizens of the United States, residing at Dayton, in the county of Montgomery and State of Ohio, have invented certain new and useful Improvements in Letter-Canceling Machines, of which the following is a specification, reference being had therein to the accompanying drawings.

This invention relates to certain new and useful improvements in machines for canceling and stamping the time, place, and date on mail-matter.

15 The objects of this invention are, first, to provide mechanism for indicating on each piece of mail-matter the exact time it is canceled without the necessity of stopping the machine to set the time-printing mechanism for each successive piece of mail-matter, the mechanism being automatically so set or operated by means of clock mechanism; second, to provide improved feeding mechanism which will release the mail-matter at the 20 proper time to allow it to momentarily remain still while being operated upon by the printing mechanism.

25 This invention also relates to details of construction hereinafter appearing, and particularly pointed out in the claims.

In the accompanying drawings, on which like reference characters indicate corresponding parts, Figure 1 is a plan view; Fig. 2, a side elevation with the parts broken away to show 30 the interior operating mechanism; Fig. 3, a rear end elevation; Fig. 4, an inverted plan view of the base-plate and operating mechanism mounted beneath the same, such operating mechanism being shown in its normal 35 position; Fig. 5, a partial plan view showing the parts in printing position; Fig. 6, an enlarged inverted plan view of a portion of the base-plate, showing the operating mechanism located beneath the same and showing the 40 manner in which it operates; Fig. 7, a longitudinal sectional view through the plunger and printing-head, showing the manner in which the printing characters are connected with the clock mechanism; Fig. 8, a side elevation of the printing-head; Fig. 9, a front elevation of the same; Fig. 10, a sectional 45

view of such printing-head on the line x x of Fig. 8; Fig. 11, a plan view of the printing-head; Fig. 12, a detail view of the "A" and "P" wheel, (forenoon and afternoon;) Fig. 13, a detail plan view of the operating-cam; Fig. 14, a sectional view of the same on the line y y of Fig. 13; Fig. 15, a detail view of the canceling-roll inker and showing the manner in which the same is operated in and out of contact with said canceling-roll; Fig. 16, a plan view of the same; Fig. 17, a sectional view on the line z z of Fig. 15; Fig. 18, a detail front view of the dating-wheels; Fig. 19, a side elevation of the same; Fig. 20, a piece 60 of canceled and stamped mail-matter; Fig. 21, a detail perspective view of a portion of the machine, showing the canceling-roll; and Fig. 22, a detail perspective view of a portion of the machine, particularly showing the 65 kicker, driving mechanism therefor, and a slot in cross-partition through which the kicker operates.

This machine has been designed to pass the mail-matter through very rapidly and at the 70 same time cancel the postage and stamp thereon the exact time of canceling, as also the place and date, such time being indicated by a clock-face.

It is often of great importance for the receiver of the mail to know the exact time when such mail-matter was canceled and is a safe criterion by which to calculate the exact time between the sending-point and the receiving-point, which may be alike both beneficial to the receiver as also the sender in numerous ways.

In order to obtain a better understanding of this invention, it will be understood that it is composed of three principal features— 80 namely, postal feeding and canceling mechanism, time, place, and dating mechanism, and mail delivering or releasing mechanism.

We will first describe the postal feeding and canceling mechanism, such mechanism being 85 adapted to feed the mail-matter into position for it to receive the impression of the stamping mechanism and also into position to be acted upon by the mail delivering or releasing mechanism.

Upon a suitable pedestal A is mounted a platform B, such platform having the same

dimensions as the dimensions of the flanges C projecting from the upper end of the pedestal. Projecting beneath such platform is a box-like structure or housing D, which extends within the recess E in the upper face of the pedestal. Within this housing is mounted all of the operating mechanism, which extends beneath the platform, so that it is kept free from dust and other foreign matter which might disturb the free and easy working of the machine. From each side of the platform and at the rear end thereof extends a table F, such table being flush with the top of the platform and supported at its rear end by means of a leg or standard G. Mail-guiding partitions H and I, respectively, project upward from the platform or table on either side of the printing and dating mechanism sufficiently to prevent the mail-matter from being interfered with by the various mechanisms contained in the machine. The space upon the feeding side of the machine we will term the "feeding-space" and indicate the same by the letter J, while the space K on the opposite side of the machine we will term the "delivering-space," it being the space into which the mail is projected as it passes through the canceling and stamping operating parts of the machine, as will hereinafter appear. From Fig. 1 particularly it will be observed that the feeding-space has a long slot L therein. Above this slot is mounted a slide or follower-plate M, such slide having a hole N therein through which extends a hand-screw O, having a handle P. From Fig. 3 it will be observed that this hand-screw is screwed into the guide-plate Q, which projects into the said groove and acts to guide the slide M along the slot. To the slide is secured one end of a cord which passes over a pulley R, mounted in the outer end of the slot. The other end of said cord is secured to a drum S, which is supported by a bracket T, carried by the flange C, and has secured to it one end of a spiral spring U, the other end of which is preferably secured to a shaft V, as shown at W. When the slide or follower-plate M has advanced into close proximity to the pulley R, the spiral spring has wound the drum and most of the cord thereon. As the slide is moved to the other or outer end of the slot such spring is unwound, and consequently will immediately act on the slide to return it to its normal or inner position, the hand-screw acting to limit or hold the slide in any desired position for the purpose hereinafter appearing. At one end of the feeding-space is mounted a plate or cross-partition 2, secured to the base-plate or platform by means of screws 3. This plate or partition is slotted, as shown at 3' in Fig. 3 and Fig. 21 particularly. From Fig. 2 it will be observed that this slot has its edges dovetailed, as shown at 4, for the reception of a sliding feed 5, such feed having teeth projecting toward the center of the machine and extending through the plate 2 for the pur-

pose of engaging with mail-matter to feed it into engagement with feed-rolls hereinafter described. To the back end of the feed 5 is pivoted one end of a pitman 9, as shown at 10, while the other end of the pitman is carried by a stud 11, projecting from a reciprocating yoke 12, such yoke being pivoted, as shown at 13, for the purpose of permitting such reciprocation. This yoke is reciprocated by means of an eccentric 14, fixedly mounted on the upper end of a shaft 15, such shaft projecting downward through the base or platform of the machine and carrying at its lower end a miter-gear 16 and extending within a stepped support 17. The gear 16 meshes with and is driven by a driving-miter 18, which is placed on the inner end of a shaft 19, extending through the sleeve 20, screwed through the casing or box D, the outer end of said shaft being adapted to receive a pulley 21 or other suitable driving device—say for driving the machine by hand. Thus as the pulley is rotated the shaft 15 is rotated, and consequently the feed device 5 is caused to operate back and forth to feed the mail-matter to the feed-rolls above mentioned.

Referring again to the shaft 15, it will be understood that this is the main driving-shaft and that upon it is mounted not only an operating-cam 22, but the main driving-gear 23, the latter of which acts to drive the feed-rolls, as also the canceling-roll and the ejecting-rolls, to be referred to hereinafter. This main driving-gear has spur-teeth 24 on its outer periphery and on its under side carries bevel-teeth 25. A spur-driven gear 26 meshes with the spur-teeth 24 of said driving-gear, such driven gear being mounted on the lower end of the feed-roll shaft 27 and having a bearing at its upper end in a bracket 28, screwed or otherwise secured to the base or platform by means of screws 29. Above the base and upon said shaft are mounted two feed-rolls 30 and 31, respectively, each of which has its periphery cut out a like extent, as shown at 32 in Fig. 1, such cut-out portions in the feed-rolls standing one above the other. It will also be understood that there is a space between them, in which reciprocates the pitman 9, above described. These rolls project slightly through the plate or partition 2, so that they will engage or come in contact with mail-matter fed to them. Opposite the roll 31 is mounted another feed-roll 34, similarly constructed, upon the shaft 35, carried in yieldable bearings 36 and 37, respectively, one of which is carried by one arm of a bracket 38, secured to the base by means of screws 39 or in any other suitable manner, and the other of which is carried by the base. Since both of these bearings are similarly mounted, a description of one will answer for both. Between the movable bearings 36 and the inner end of slot 37' in the bracket is interposed a spring 38', carried by studs 39 and 40, projecting from the inner end of the slot and bearing, respectively. Thus the yieldable

bearings are held to the outer ends of the slots, so that the roller 34 will be pressed sufficiently close to the roller 31 to permit of gripping mail-matter to feed it to the printing mechanism. In order, however, to limit the pressure of the roller 34 upon the roller 31, we provide a set-screw 35, which acts to limit the movement of the bearing 36 toward the front of the slot. Opposite the feed-roll 30 is mounted a canceling-roll 41, such feed-roll being constructed of brass, alloy, or other suitable material. This canceling-roll also has its periphery cut out to match the feed-roll mounted above it, there being a similar space 42 between such feed-roll and such canceling-roll as between the feed-rolls 30 and 31. On the lower end of the shaft 35 is mounted a miter-gear 43, which meshes with a similar gear 44, slidably supported on the shaft 45, such shaft 20 being mounted in a fixed bearing-bracket 46 and a sliding bearing-bracket 47, the latter of which is adapted to slide in ways 48, screwed or otherwise secured to the under side of the base, such sliding bearing-bracket 25 being for the purpose of permitting the canceling-roll and the feeding-roll both to be separated from their adjacent rolls at predetermined times, so that the mail-matter will be released at such times by the roll, for the 30 purpose hereinafter appearing.

We have now described the manner in which the feeding-rolls and the canceling-roll are mounted and also the manner in which they are driven. Before leaving this branch 35 of the subject we will describe the inking device for inking the canceling-roll.

By referring to Fig. 15 it will be seen that to the inner side of the partition H we have mounted a sliding plate 49 in a dovetailed groove 50 in said plate. To this sliding plate is pivotally secured an inking-roll bracket 51 by means of a screw 52. The inking-roll bracket is bifurcated and has mounted in such bifurcation a collar 53 upon a shaft 54, 45 projecting upward from the inking-roll 55 into the bracket. The collar 53 is pinned or otherwise secured to said stem by means of a pin 57. A spring 58, mounted on studs 59 and 60, acts to hold the inking-roller in contact 50 with the canceling-roll. In order to disengage the inking-roll from the canceling-roll, whereby the canceling of the postage may be omitted, we provide a pivoted sector 61, pivoted upon a stud 62, screwed in the partition H. 55 This sector engages with a rack 63, carried by a slide 49. The upper end of the sector carries a handle 64 and a screw-threaded detent 65, the latter of which is adapted to screw into the depression 66 in the plate when the inking-roll is in inking position and into another depression 67 when the sector has raised the inking-roll out of inking contact with the canceling-roll. (See Figs 15 and 16.) As soon 60 as the inking-roll is removed from contact 65 with the canceling-roll such roll will fail to properly cancel the postage, as there is no ink on the canceling-roll for such purpose.

Referring now to the printing and dating mechanism, (see particularly Fig. 7,) it will be observed that it is composed of a plunger 68, 70 extending through a bracket 38 and through a support 38", and on the outer end of which is mounted a printing-head 69. This plunger is bored out longitudinally, as shown at 70 in Fig. 7, and within such hole is mounted a hollow shaft 71, which we term the "hour-shaft," such shaft being enlarged at its forward end, as shown at 72. Upon the outer end of this enlargement projects a V-shaped or arrow-shaped figure 73, (see Fig. 9,) which is adapted 80 to indicate the hour on a clock-dial 74, surrounding such enlargement, in a manner hereinafter appearing. Within this hollow shaft is mounted another shaft 75, which we term the "minute-shaft." This shaft is also enlarged at its outer end, as shown at 76, and has mounted upon such enlarged end a raised figure representing the minute - hand of a clock, as indicated at 77, (see Fig. 9,) such hand being also rotatable to indicate various 90 hours on the clock-dial above referred to. We will refer to the manner in which these shafts are operated. On the platform or base is mounted a clock of any ordinary or approved type, as indicated at 78. To the minute-post of such clock is secured a slotted sleeve 79 by means of a pin 80, within whose outer end is mounted the inner end of the minute-shaft 75, such minute-shaft being made to turn with the sleeve by means of a pin 81, such pin, however, permitting the minute-shaft to move back and forth in the slotted sleeve 79. Near the inner end of the plunger 68 is mounted a spur-gear 82 upon the minute-shaft, such spur-gear being secured to said shaft by means of a pin 83. This spur-gear meshes with a double spur-gear 84, which is rotatably supported by a projection 85, extending upward from the plunger. Another spur-gear 86, carried by 105 the inner end of the hour-shaft, also meshes with the said double gear. Thus the movement of the clock is transmitted to the minute and hour shafts, and the gears just described have such relation to each other that 110 the hour-shaft rotates with the correct relative speed to the minute-shaft. Beneath the dial 74 on the plate 89 is formed in raised letters the name of the post office, together with the name of the State, while on the right-hand side of the dial, as viewed in Fig. 9, is formed the letter "M," and on the left-hand side the letter "A" or "P" is exhibited, according to whether before or after noon, such letters being formed on the periphery of the 115 "A" and "P" segment, as illustrated at 90 in Figs. 10 and 12. This "A" and "P" segment is mounted on a shaft 92, carrying on its outer end a crank 93, pinned or otherwise secured thereto, by which the shaft is rotated 120 to bring the proper character into the opening 91. A cap 94 acts as a support for the shaft 92 and is let into the side of the head 95 and held in such position by means of a

screw 95 engaging with the cap and head. In order to hold the letters "A" and "P" in their exposed position, the outer end of the crank 93 is provided with a spring-detent 96, 5 which is adapted to engage with one or the other of the holes or depressions 97 in a cap 98, such cap acting to hold dating-rings within the head 69. This cap is secured to the head by means of screws 99 engaging with 10 both the head and cap. A shaft 100 extends longitudinally through the head 69 and has mounted upon it numerous dating-rings *a, b, c, d, and e.* (See Figs. 1 and 18 particularly.) The ring *a* has the names of the months thereon, while the ring *b* has numbers thereon from "0" to "9," inclusive, and on the ring *c* from "1" to "3," inclusive. This latter ring may have several series of such numbers. The rings *d* and *e* are numbered to correspond with the year in which they are to be used, such as the year "99," &c. To each of these dating-rings are secured ratchet-plates 15 *f, g, h, i, and j*, respectively, such ratchet-plates being adapted to be engaged by pawls *k*, pivotally mounted above them upon a pin *m*, such detents projecting through slots in the upper face of the head 69. (See Figs. 7 to 10.) These detents extend rearwardly from the pin *m*, and beneath such 20 rear ends are mounted little springs *n*, let into cups *o*. Let us suppose it is desired to change the month, say December to January. This is accomplished by means of a spanner or other suitable device adapted to engage with 25 the spanner-sleeve 101, which projects from the month-ring *a* and is enlarged at its outer end in the form of a disk, having suitable notches 102 therein. As this ring is turned so as to present the new month one of the 30 pawls *k* engages another tooth of the ratchet-wheel *f*, thus holding said wheel in its set position. From the dating-ring projects a sleeve 103, which fits upon the sleeve 101. This sleeve is also provided with a notched spanner-disk 104, by which the sleeve and dating-ring may be rotated. The ring *c* is also 35 provided with a sleeve 105, mounted upon the sleeve 103 and likewise provided with a notched spanner-disk 106. The rings *d* and *e* 40 are also provided with sleeves 107 and 108, respectively, and each provided with a notched spanner-disk 109 and 110, respectively. Of course it will be understood that the numbers and characters on these dating-rings are raised 45 in a manner similar to that shown in Fig. 19 at 111. We have now described the manner in which the time is indicated in the dating mechanism and how such mechanism is manipulated to present the proper date, and we 50 shall proceed to describe the manner in which such dating and printing mechanism is inked.

It will be seen that to the under side of the base or platform is pivoted a lever 112 (see Fig. 6) upon a pivot 113. One end of this 55 lever carries a roller 114, which is mounted in the path of the cam 22 on the main driving-shaft 15, as stated heretofore. The other end

of the lever is slotted, as shown at 115, and engages with the roller 116, carried by a clamping-collar 117, adapted to embrace a shaft 118 70 and be clamped thereto by means of a screw 119. The shaft 118 projects upward through the base and has mounted thereon a bifurcated bracket 120. (See Fig. 7.) This bifurcated bracket has pivoted between its bifurcated ends inking-roller shanks 121, carrying an inking-roll 122, such inking-roll being carried to one side of the plunger and inking-head above described. When the parts are in position as indicated by full lines in Fig. 4, the 80 inking-roll just described is in the position indicated in Fig. 1. While in such position, it will be observed that the head 69 is flush with the curved plate 123, which acts as a guide to guide the roller onto the inking-face 89. A 85 spring 124 normally holds the inking-roll in engagement with such curved plate and presses it against the inking characters as the inking-roll is operated to the dotted position as indicated in Fig. 1 in a manner presently to appear. By referring to Fig. 4 it will be seen that the cam 22 is in such position that the lever 112 will remain inoperative; but as the machine is set in motion the cam will travel in the direction of the arrow and will move the lever 90 112 from the full-line position as shown in Fig. 4 to the full-line position as shown in Fig. 6 or from the dotted position in Fig. 6 to its full-line position. This movement will cause the shaft 118 to be partially rotated, 100 and since the bifurcated bracket is rigidly connected therewith it will be advanced, together with the inking-roll 122, carried thereby. This will cause the inking-roll to travel across the face of the printing-head to the 105 position illustrated in dotted lines in Fig. 1, thus inking the printing characters. As the cam is still further operated the roller 114, together with its lever 112, will be returned to its normal position, thereby returning the 110 inking-roll to its normal position. The next operation which takes place is the advancement of the plunger 68 to impress the mailer with the date and other data desired. We will now describe the manner in which 115 this is accomplished. It will be observed that to the under side of the base or platform is pivotally mounted a radius-bar 125 upon a stud 126. (See Fig. 6.) To the opposite end of this radius-bar is pivoted the 120 plunger-pitman 126', while a short distance from the end of such bar is carried a roller 127 in the path of the cam 22. When the cam advances from its normal position, as 125 shown in Fig. 6, until the portion of its circumference *A'* as indicated by the arrows *A'* moves nearly one-half of a revolution, the plunger-pitman will be at rest, thus permitting the inking-roller to perform its function; but as the cam continues to advance 130 until the portion *A'* travels around to the position *B'* (indicated by the arrows *B'*) or substantially three-quarters of a revolution (see Fig. 6) the roller 127 will be thrown to its rear

dotted-line position and the pitman 126' will be advanced to its dotted-line position. This will partially rotate the stud-plate 128 from the full-line position around to the dotted position, as also shown in Fig. 6. The plate 128 is rigidly attached to the lower end of a sector-shaft 129, which projects upward through the base and has mounted upon its upper end a sector 130. (See Figs. 1 and 5.) This sector 5 engages with a rack 131, bolted or otherwise secured to the side of the plunger 68. From the stud-plate 128 projects an arm 132. (See Fig. 6.) Such arm has secured to it at its outer end a spring 133, which is secured at its other end to a pin 134, projecting downward from the base. This spring is normally mounted under tension, so that when the cam has advanced to substantially B' position the roller 127, together with the pitman 126, will be instantaneously moved forward to its dotted position. (Illustrated in Fig. 6.) This will cause the sector engaging with the rack 131 to be thrown to its full-line position as indicated in Fig. 5. As the cam rotates from the position B' through the arc of a circle C' it will cause the roller 127, as also the pitman 126, to return to its normal position, thus operating the sector in the opposite direction to cause the plunger to return to its normal position, as indicated in Fig. 1.

We have now described the manner in which the plunger, together with the printing-head, is carried forward to and returned from its printing or stamping position.

35 We will now refer to the mail delivering or releasing mechanism. (See Figs. 1 and 5.) This consists of a pair of rolls similar to the feed-rolls and arranged in line therewith, as also a device for forcing the mail-matter out 40 of the path of the next piece of mail-matter. On the shaft 135 is mounted these releasing-rolls 136 and 137, respectively. The upper end of the shaft 135 is supported in the bearing 138 in the bracket 28, while its lower end 45 projects through the base and has mounted therein a bevel-gear 139, (see Fig. 6,) such bevel-gear meshing with a similar gear 140, carried by a shaft 141, supported by one branch 142 of the bifurcated bracket 143. 50 The other end of said shaft carries a bevel-gear 144, which meshes with a bevel-gear 145 upon the under face of the gear 23. The gear 139 transmits motion to a gear 146, supported on one end of a shaft 147, such shaft being 55 mounted on a slideable bearing 148 and in the bifurcated bracket 143. Between these bearings and upon the shaft is mounted a sleeve miter-gear 149, which meshes with a miter-gear 150, mounted on the lower end of a releasing-roller shaft 151, such shaft extending 60 upward through the base and into a yieldable bearing 152, carried by the bracket 38, which is slotted to receive such bearing and permit it to move therein. A spring 153 is placed 65 between the yieldable bearing and the inner end of the slot 154 and is mounted upon centering-pins 155 and 156, carried by the bracket

and yieldable bearing, respectively. A limiting-screw 157 limits the movement of the releasing-rolls 158 and 159, respectively, toward the releasing-roll 136, above described. It will be understood that the releasing-rolls 158 and 159 have a portion of their periphery cut away in a manner similar to the feed-rolls heretofore described for the purpose herein- 70 after appearing. The shaft 151 also extends through a yieldable bearing in the slotted base, such bearing being shown at 160. A spring similar to the spring 153 is mounted between the bearing and the rear end of the 80 slot in the base, as indicated at 161, and is also mounted upon centering-pins 162 and 163. Thus it will be seen that the releasing-rolls 158 and 159 are yieldably mounted. This is 85 for the purpose of permitting various thicknesses of mail-matter to readily pass between the releasing-rolls. Upon the releasing-roll shaft 135 is mounted a spur-gear 164, which is keyed or otherwise secured thereto. This spur-gear is between the releasing-rolls 136 90 and 137 and is adapted to mesh with an idler-gear 165, carried by a bracket 166, screwed or otherwise secured to the plate or partition 2. This bracket also supports the driven gear 167, to the upper face of which is screwed a 95 curved stem 168, which is adapted to rotate through a slot 169 in the partition 2 for the purpose of pushing or kicking mail-matter away from the next succeeding piece of mail-matter as it leaves the releasing-rolls above 100 referred to.

Referring now to the operation of the machine, it will be understood that the mail-matter is placed within the delivery-space J between the partition 2 and the follower-plate 105 M, such follower-plate being moved along the slot L to accommodate the varying number of letters and other mail-matter which may be placed upon the table. As soon as such letters are in position the screw-handle P is released and the action of the spiral spring U causes the follower-plate to push such letters along the delivery-space and hold them snugly in contact with the feed-plate, which 110 engages one letter at a time and feeds the 115 same into the feeding-rolls, so that they may act on such mail-matter to feed the same along beyond the printing-head to the dotted position, as shown in Fig. 5 at a'. While mail-matter has been advanced to this position, the inking-roll 122 has been operated across the inking-head and back to its normal position, ready for the head to print the date, the time, and the place on said mail-matter, such printing being accomplished by 120 the advancement of the printing-head into contact with such mail-matter in the manner heretofore described. It will be understood, however, that as the printing-head advances into contact with the mail-matter the feeding-rolls separate or spread apart, so as to free 125 themselves from such mail-matter. This spreading of the feed-rolls is accomplished by means of the lever 170, (see Fig. 6,) pivoted 130

upon a stud 171, carried by the under side of the base. To this lever is secured a pitman 172, which engages with one of the levers 173, pivoted upon the stud 174. The other end of the lever 173 carries a roller 175, which travels in a cam-groove 22. When the cam operates this lever so that it travels from the full-line position as shown in Fig. 6 to its dotted position, shown broken away, the lever 170 will slide the bevel-gear 44 on the shaft 45, which action will cause the movable feed-roll shaft 35 to move backward with its bearings. As soon as the lever 173 is returned to normal position by means of said cam the yielding bearings will be thrown to their normal position by means of their springs above described. As soon as the printing-head returns to its normal position the feed-rolls again come into position to again grip the mail-matter and advance it into position for the releasing-rolls to engage therewith. The delivery-rolls travel about twice as fast as the feeding-rolls, and in order to prevent them from engaging with the mail-matter before the feeding-rolls have released them we have cut away a portion of the periphery of the delivery-rolls 158 and 159, which will delay the engagement of such mail-matter by such delivery-rolls. This arrangement prevents the mail from being gripped by both the delivery and feeding rolls at the same time and from tearing the mail.

Referring again to the feeding-rolls, it will be understood that they are cut out, as heretofore described, for the purpose of more surely disengaging the mail-matter, particularly where such mail-matter is longer than the usual size. It will further be understood that as the mail-matter passes between the feed-rolls it is canceled by means of the canceling-roll above referred to. Thus with our invention we have provided for not only canceling the mail-matter, but also for stamping upon it the exact time of cancellation, the date, and the name of the post-office.

Referring now to the mechanism for widening the receiving and feeding spaces, it will be understood that we have provided side rails 175, which are supported by pivoted standards 176, pivoted to base-rails 177, supported in bearings 178. These side rails are each connected with a lever 179 by means of connecting-bars 180, such lever being pivoted on the stud 181, carried by the inner end of the table or platform. (See particularly Fig. 3.) The upper end of said lever is provided with a handle 182, which has a stem 183, adapted to engage with a detent 184, supported in a bracket 185, projecting from said lever. (See Fig. 2.) This bracket is adapted to engage with notches 186 along the inner edge of the curved bar 187, secured at its end to the partitions H and I, respectively. To the side rails 175 are secured side plates 189, respectively. These side plates are adjusted with the side rails, which are readily

shifted in or out by means of the lever 179 through its connection therewith.

Referring again to the delivery-space, it will be observed that in it is mounted a sliding holder 190, (see Figs. 1 and 3,) which stands across the space and at its inner end is turned at right angles and carries rollers 191, which ride upon the upper edge of the partition I. This sliding holder rests upon the table or platform, and as the mail-matter is projected into the delivery-space the kicker 166 forces the mail against said holder and causes it to travel backward within the delivery-space and yet holds such mail-matter from falling down upon its flat side, so that it travels backward in the delivery-space upon edge.

Referring again to the partition H, it will be observed that on its outer end is mounted fingers *a'*, (see Figs. 1 and 16,) preferably composed of spring material secured to the partition by means of screws *b'*. These spring-fingers project sufficiently to prevent more than one piece of mail-matter passing through the feed-rolls at one time. It will also be observed that there is let into the partition 2 in front of the printing-head a cushion 191, held in position by means of screws 192. This cushion prevents the characters on the printing-head from becoming injured should the printing-head be operated without any mail-matter in the machine. (See Figs. 1 and 5.) Should the clock run down or should it break or be omitted, the time-printing device can be set by taking hold of gear 84 with the fingers and turning the hour and minute shafts 71 and 75.

Thus it will be seen that we have provided a machine of the character described and have set forth and illustrated one (the preferred) type of detail organization and construction, which machine does these things, namely: It feeds the mail-matter to the printing position. Its feeding mechanism then ceases to act on the mail-matter, so that it is in a state of momentary rest while being printed upon, (in which term we include date and place printing and time-printing.) It then delivers or discharges the printed matter, and it finally kicks or ejects such matter back and away from the active parts of the machine along the delivering-space, and it continuously indicates the time such printing operations are performed and all this without stopping the machine or requiring any manual adjustments or manipulations other than the application of the motive or driving force. We would further observe that if the clock were removed or omitted altogether from the group above recited the remaining functions and devices will be within our contemplations and be highly useful, the time-printing device being in such case hand-set.

Having thus fully described our invention, what we claim as new, and desire to secure by Letters Patent, is—

1. In a machine for canceling and stamping mail-matter, the combination with a suitable base, of feeding mechanisms, consisting of a reciprocating feed-plate and feed-rolls for feeding mail-matter, mounted thereon, dating, time-printing and canceling mechanisms, and a timepiece directly connected with said printing mechanism for continuously operating such mechanism, and means for automatically reciprocating said dating and time-printing mechanism into and out of printing contact with mail-matter advanced into printing position by said feeding mechanisms.

2. In a machine for canceling and stamping mail-matter, the combination with a base, of feeding mechanism consisting of a sliding feed and feed-rolls adapted to feed mail-matter, a canceling-roll for acting upon said mail-matter as it is being fed, a dating and time-indicating mechanism, slidably mounted, for impressing said mail-matter after passing said feed-rolls and canceling-roll, clock mechanism for controlling the movement of said time-indicating mechanism, and means to impress the printing characters on said mail-matter, substantially as shown and described.

3. In a machine for canceling and stamping mail-matter, the combination with a base having suitable mail-matter-feeding mechanism mounted thereon, as also canceling mechanism, of a plunger carrying a printing-head at its outer end, dating mechanism, and time-indicating mechanism mounted therein, said plunger and its head being adapted to move longitudinally to impress said mail-matter with said dating and time-indicating mechanisms.

4. In a machine for canceling and stamping mail-matter, the combination with a base having suitable feeding mechanism mounted thereon, of a canceling-roll, connected with said feed mechanism, a plunger carrying a printing-head mounted in close proximity to said feeding mechanism, a hollow shaft or sleeve extending through said plunger and carrying an hour-indicating device on its outer end, a shaft extending through said sleeve and carrying on its outer end a minute-hand and connected at its inner end with suitable clock mechanism, and gears between said shaft and sleeve to regulate the movement of the sleeve, dating mechanism carried by said head and rotatably mounted therein, and means to hold said dating mechanism in its proper position to indicate the month, the day of the month and the year, and means to operate said plunger and printing-head into and out of engagement with said mail-matter, and delivering means for delivering the mail-matter from the path of said plunger, substantially as shown and described.

5. In a machine for canceling and stamping mail-matter, the combination with a base or platform having a feeding-space and a delivery-space thereon, of feeding mechanism composed of a toothed sliding plate and feeding-rolls, such toothed sliding plate adapted

to engage with one piece of mail-matter at a time and present it to said feeding-rolls, a canceling-roll mounted on one of said feed-roll shafts and adapted to cancel said mail-matter as it passes between said rolls, dating and time-printing mechanism mounted in close proximity to said feeding-rolls, inking devices for inking said canceling-roll and said printing mechanism, and means to reciprocate said printing mechanism into contact with said mail-matter, and delivering mechanism for delivering the mail-matter from the path of said printing mechanism into said delivering-space.

6. In a machine for canceling and stamping mail-matter, the combination with a base, of feed-roll shafts projecting through said base and upward therefrom, fixed bearings for one of said shafts, a yieldable bearing for each end of the other of said shafts whereby said yieldable shaft may be separated from said fixed shaft in such a manner that each of said shafts may be parallel to each other, a pair of feed-rolls mounted on one of said shafts, one above the other with a space between them, and a feed-roll and a canceling-roll mounted on the other of said shafts with a space between them, said upper feed-rolls adapted to contact with each other and said lower feed-roll and canceling-roll also adapted to contact with each other, gear mechanism connected with the lower ends of said feed-roll shafts and adapted to drive them, and a yieldable inking-roll for inking said canceling-roll, substantially as shown and described.

7. In a machine for canceling and stamping mail-matter, the combination with a base having a pair of feed-roll shafts thereon, of driving mechanism connected with the lower ends of said shafts and adapted to rotate them, yieldable bearings for one of said shafts and fixed bearings for the other of said shafts, a pair of feed-rolls mounted on one of said shafts and a feed-roll and canceling-roll mounted on the other of said shafts, each of said feed-rolls and canceling-roll having a portion of its periphery cut away whereby throughout a portion of their rotation they will be out of contact with mail-matter, and an inking device for inking said canceling-roll, and a reciprocating device for impressing mail-matter passing between said rolls when said rolls are out of contact with said mail-matter, substantially as shown and described.

8. In a machine for canceling and stamping mail-matter, the combination with a base or platform, of a plunger carrying a printing-head at one end, a minute-shaft and an hour-shaft extending through said plunger, time-printing characters carried at one end of each of said respective shafts and adapted to work in conjunction with and form a part of said printing-head, a double gear carried by the end of said plunger opposite the printing-head, a gear on said minute-shaft meshing with one set of gear-teeth on said double gear, a gear on said hour-shaft meshing with the

other of said double gears, a clock for driving said minute-shaft, and means to automatically reciprocate said plunger, together with said hour and minute shafts, said minute-shaft 5 being reciprocatingly connected with said clock mechanism, substantially as shown and described.

9. In a machine for canceling and stamping mail-matter, the combination with a base or 10 platform, of an automatically-reciprocating plunger mounted thereon and means to effect such reciprocation, said plunger carrying a printing-head at its forward end, time-indicating mechanism carried by said printing- 15 head and adapted to be continuously operated by a clock, dating mechanism also carried by said head and adapted to be adjusted to change the date, means to indicate whether a. m. or p. m., and inking means for inking 20 said printing-face, substantially as shown and described.

10. In a machine for canceling and stamping mail-matter, the combination with a base or platform, of a plunger having a longitudinal 25 hole therein and carrying at its outer end a printing-head, a sleeve or hour shaft mounted in said longitudinal hole, a minute-shaft mounted in said hour-shaft and reciprocatingly connected with a clock, gears between 30 said hour and minute shafts for giving the proper relative movement, a head carried by the hour-shaft and having an hour-indicating character thereon, and a head carried by said minute-shaft having a minute-indicating 35 character thereon, such characters forming a printing-surface in the face of the printing-head, dating rings or disks mounted in said head upon a shaft, each of said rings having a ratchet secured thereto or projecting there- 40 from, pivoted detents engaging with said ratchets, and springs for holding said detents normally in engagement with said ratchets, a sleeve projecting from each of said disks and having a flange with notches therein for 45 inserting a spanner, whereby the dating rings or disks are partially rotated for changing the dates, and an inking-roller adapted to pass over the face of said printing-head and withdraw therefrom, and means to reciprocate said 50 plunger, and other means to operate said inking-roll, substantially as shown and described.

11. In a machine for canceling and stamping mail-matter, the combination with a base or platform, of a reciprocating plunger carrying a printing-head at its forward end, dating characters, time characters and the name of the town or city, together with the name of the State, characters, appearing in the face of said printing-head, clock-controlled means 55 for indicating the time by said characters, and hand means for manipulating the dating characters, and hand means consisting of a crank together with a spring-pressed detent in its handle for changing the "A" and "P" disk to 60 represent forenoon or afternoon, and the letter "M" also appearing in the printing-head on the opposite side of the dial from the "A" and

"P" disk, an inking-roll for engaging the face of said printing-head and withdrawing therefrom, and means for automatically reciprocating said plunger, all substantially as shown and described. 70

12. In a machine for canceling and stamping mail-matter, the combination with a base or support carrying a printing-head, of an inking-roll support mounted thereon, a bifurcated bracket pivotally connected with said support, inking-roll arms pivotally connected with said bracket, an inking-roll mounted in said arms, and a spring engaging with one of said arms and having its other end connected with said bifurcated bracket, a shaft also engaging with said bifurcated bracket and extending beneath the base or platform, a plate secured to its lower end and carrying a crank-stud, a lever fulcrumed to the base and having one end engaging with said crank-stud and its other end carrying a roller, a cam adapted to engage with said roller to rock said lever and thereby operate the inking-roll back and forth across the face of the printing-head, substantially as shown and described. 80 85 90

13. In a machine for canceling and stamping mail-matter, the combination with a base or platform carrying printing mechanism, of a support mounted thereon, a bifurcated bracket pivoted upon said support, an inking-roll hinged to said bracket, a spring between said inking-roll and bracket, a curved plate upon which said inking-roll is adapted to travel and against which it is held by said spring, a shaft connected with said bifurcated bracket, a clip adapted to embrace the lower end of said shaft and secured thereto by means of a screw, a stud projecting from said clip, a pivoted lever having a slot at one end into which said stud extends, a roller carried by the other end of said lever and adapted to engage with a driving-cam whereby said lever is rocked and said inking-roll is carried across and withdrawn from the printing mechanism. 105 110 115

14. In a machine for canceling and stamping mail-matter, the combination with a base or support having a pair of shafts extending upward therefrom, one of which shafts has a stationary bearing and the other of which has a yieldable bearing, a pair of delivering-rolls mounted on each shaft, one above the other, with a space between them, the periphery of one pair of said rolls on one shaft being cut out, and means for rotating said shafts, substantially as shown and described. 120 125

15. In a machine for canceling and stamping mail-matter, the combination with a base, of a main driving-shaft extending downward therefrom, a driving bevel-gear mounted on said shaft, a bifurcated bracket secured to the base and carrying a shaft in one arm thereof, a pair of bevel-gears mounted on the respective ends of said shaft, one of which meshes with said driving bevel-gear, and the other of which meshes with a bevel-gear on the lower end of a delivering-roll shaft, a 130

shaft having one end mounted in the other arm of said bifurcated bracket and at the other end supported by the slidable bracket, a bevel-gear engaging with said delivering-
5 shaft gear and also carrying another bevel or miter gear slidable thereon and adapted to engage with a driven miter-gear carried on the lower end of a second delivering-roll shaft, said delivering-roll shaft mounted on yieldable bearings whereby it will yield to accommodate various thicknesses of mail-matter, and delivering-rolls mounted on said shaft, substantially as shown and described.

16. In a machine for canceling and stamping mail-matter, the combination with a base or platform having a pair of guiding-partitions mounted thereon, of a pair of side plates supported above said base or platform to form a space between them and said partitions, 15 said plates hung upward on said side rails, a lever fulcrumed near the inner end of said base or platform and a pair of connecting-rods connecting their respective side rails with said lever at either side of its pivot, a 20 segment having notches therein rigidly connected with said machine and a detent carried by said lever adapted to engage in said notches, said lever being adapted to move so that its detents may engage in one of said 25 notches whereby the side plates and side rails may be adjusted in or out over the platform, as desired, and held in such adjusted position.

17. In a machine for canceling and stamping mail-matter, the combination with a base or platform having a delivering-space thereon, said base being slotted in said space, a follower-plate mounted upon said base over said slot, a guide-plate beneath said base and 30 adapted to extend into said slot, and a clamping-screw adapted to extend through said follower-plate and into said guide-plate, a cord adapted to engage with said follower-plate and with a spring-operated drum to draw 35 said follower-plate and guide-plate along said slot when not locked by the clamping-screw.

18. In a machine for canceling and stamping mail-matter, the combination with a base or pedestal cupped out or depressed at its 40 upper end and having flanges extending from its upper edges, a canceling and stamping machine proper having a base or platform, and a casing projecting downward therefrom, said casing adapted to fit within the depression in said pedestal and said base or platform upon the flanges extending from said pedestal, substantially as shown and described.

19. In a machine for canceling and stamping mail-matter, the combination with a base or platform having a feeding-space and a delivering-space thereon, a pair of partitions having a space between said feeding and delivering spaces, adjustable outer sides for 45 each of said outer spaces and a follower-plate in said feeding-space adapted to press mail-matter into contact with a feeding-plate, said

feeding-plate acting to deliver said mail-pieces one at a time to the feeding-rolls, a canceling-roll adapted to act upon said mail-matter as it passes between said feed-rolls, 50 dating and time indicating mechanism near said feed-rolls adapted to impress said mail-matter when free from said rolls, delivering-rolls adapted to deliver the mail-matter into 55 said delivering-space after being acted upon by said printing mechanism, displacing or kicking mechanism for quickly throwing said mail-matter out of the path of the succeeding piece of mail-matter, and a holding-plate 60 within said delivering-space for holding the mail-matter from falling over when acted upon by said kicking mechanism, all substantially as shown and described.

20. In a machine for canceling and stamping mail-matter, the combination with a base, having a casing extending downward therefrom, of a main driving-shaft having a bearing near its upper end in said base and a step-bearing for its lower end carried by said casing, a pair of ears and a cam and eccentric plates rigidly mounted thereon, one of said gears having a spur-tooth and a bevel-tooth, feed-roll shafts carrying gearing adapted to mesh with said spur and bevel gears, feeding-rolls having gears on their lower ends adapted to mesh with said spur and bevel gears, a pivoted yoke adapted to engage with the upper of said cams, a pitman pivotally connected with said yoke, and with a reciprocating feed-bar to reciprocate it, a canceling-roll, 90 also carried by one of said feed-roll shafts, and a plunger between the feed-roll shafts and the delivering-shafts carrying a printing-head, a rack carried by said plunger and a sector engaging therewith, said sector being operated by said cam in one direction and in the other direction by means of a spring, inking-rolls for inking the canceling-roll and printing-head, the latter of which is operated 95 into inking contact with said head by means of its connection with said driving-cam, and means to automatically spread apart said feed-rolls, said means also being driven by said cam, and clock-controlled means for indicating the exact time, on mail-matter that the printing mechanism is reciprocated to stamp 100 said mail-matter, and means to drive said main driving-shaft, all substantially as shown and described.

21. In a machine for canceling and stamping mail-matter, the combination with a partition having a slide mounted thereon, a bracket pivotally connected with said slide, an inking-roll rotatably mounted in said 110 bracket, a spring connected to said pivoted bracket at one end and with said slide-bracket at its other end adapted to normally hold said inking-roll in contact with said canceling-roll, and a rack carried by said slide, and a segment adapted to engage with said rack to raise and lower said slide, said segment engaging with said partition to hold the segment 115 in the desired position.

22. In a machine for canceling and stamping mail-matter, the combination with a suitable base, of feeding mechanism for the mail-matter, printing mechanism for said matter, substantially as this feature is described, delivery mechanism, time mechanism for continuously operating the time-printing feature, and intermediary constructions and devices by which the feeding mechanism becomes inactive on the mail-matter while the printing mechanism is impressing said matter, and by which the delivery mechanism becomes inactive upon the mail-matter when said printing operation ceases.
23. In a machine for canceling and stamping mail-matter, the combination with a suitable base, of feeding mechanism for the mail-

matter, reciprocating printing mechanism for impressing said mail-matter, delivery mechanism, and intermediary constructions and devices by which said feeding mechanism releases said mail-matter, while the printing mechanism is impressing said matter, and by which the delivery mechanism becomes active upon the mail-matter when said printing operation ceases.

In testimony whereof we affix our signatures in presence of two witnesses.
